HYPOCHOLESTEROLEMIC N-OXIDE COMPOSITIONS

Blaine M. Sutton, Philadelphia, Pa., assignor to Smith Kline & French Laboratories, Philadelphia, Pa., a corporation of Pennsylvania
No Drawing. Filed Jan. 30, 1962, Ser. No. 169,944
7 Claims. (Cl. 260—469)

This invention relates to new compounds of utility as cholesterol-lowering agents. More specifically, these compounds are N-oxide derivatives of known aminoalkyl esters of substituted diphenylacetic acids.

This invention is surprising in that I have found that certain known aminoalkyl esters of various diphenyl acetic acids have potent hypocholesterolemic activity but with toxic manifestations concomitantly occurring, such as enlarged or fatty infiltrated livers. When the new N-oxide derivatives of these parent compounds were prepared and tested, I unexpectedly found them to retain this high hypocholesterolemic activity but without side effects, for example, the livers remained normal. Furthermore, the known pharmacodynamic activity of the parent compounds, such as spasmolytic or potentiating activity, has been favorably altered in the N-oxide derivatives.

The compounds of this invention are N-oxide aminoalkyl esters of diphenylacetic acids but are more specifically represented by the following formula:

FORMULA I

in which:

R is alkylene having from 2 to 6 carbon atoms inclusive, separating the amine and the carboxylic functions by at least 2 carbon atoms, ethylene is preferred;

R₁ is alkyl or alkenyl having from 1 to 8 carbon atoms inclusive; and

R₂ and R₃ are alkyl of from 1 to 8 carbon atoms inclusive or benzyl.

The preferred compounds of this invention are those in which:

R is alkylene of 2 to 4 carbon atoms;

R₁ is an alkyl of from 3 to 4 carbons; and

R₂ and R₃ are alkyl of from 1 to 4 carbon atoms.

The preferred and advantageous compound of this invention is β -diethylaminoethyl 2,2-diphenylpentanoate N-oxide and its salts, especially the hydrochloride.

Also included in this invention, represented by structural Formula I, are various nontoxic, pharmaceutically-acceptable addition compounds. Such addition compounds may include hydrates, acid addition salts or alkyl halide addition salts. The acid addition salts are those derived from inorganic or organic acids well-known to the art as being pharmaceutically acceptable, for example the hydrohalide such as hydrochloride or hydrobromide, the sulfate, phosphate, maleate or ethane disulfonate. The alkyl halide addition compounds are also those well-known to the art as being acceptable, such as the methyl iodide, methyl chloride, crotyl chloride, benzyl chloride, ethyl bromide, ethylene bromohydrin, ethyl chloride, dimethyl sulfate, ethyl toluene sulfonate, etc. salts.

The structures of these addition compounds may be represented as:

2

FORMULA II

where R-R₃ are as described above; and R₄ in the case of the acids is hydrogen and in the halides is lower alkyl of 1 to 5 carbon atoms and X[⊖] is a nontoxic, pharmaceutically acceptable anion.

The addition products of Formula II are easily prepared by dissolving the parent compound of Formula I in a suitable solvent, such as a lower alkyl alcohol, reacting with one mole or preferably an excess of the desired acid or reactive halide to form the derivative of Formula II.

The derivatives of Formula II, particularly those in which R₄ is hydrogen, are preferred.

The N-oxide derivatives of Formula I are prepared by reacting the known tertiary amine bases with a mild oxidizing agent preferably hydrogen peroxide usually in excess at about room temperature in a solvent in which the base is substantially soluble such as in an aqueous lower alkyl alcohol solvent, preferably methanol, isopropanol or ethanol.

The compounds of Formula I in which R₁ is alkenyl must be oxidized carefully so that the vinylene moiety is retained. In this regard about 10% hydrogen peroxide concentration in the oxidation media is preferred. Also the reaction mixture should be preferably run in a vessel protected from light.

The tertiary amines which act as starting materials for the compounds of this invention are well known to the art. They are prepared for instance as reported by Craig et al., J. Am. Chem. Soc., 73, 1339 (1951), Larsen et al., J. Am. Chem. Soc., 71, 532 (1949) or more specifically by Fellows in U.S. Patent No. 2,807,566.

The amine oxide derivatives claimed herein are administered to hypercholesterolemic mammal patients in dosage unit form combined with an inert pharmaceutical carrier such as lactose, talc etc. in the form of a pill, capsule, aqueous suspension etc. The dosage unit will contain from about 25-300 mg. of N-oxide and will be administered internally preferably orally from 1 to 6 times daily. A single large dose, i.e. from about 200-250 mg., daily is preferred.

The following examples will illustrate the ease of preparation of the compounds of this invention and the availability of starting materials therefore but are not to be construed as limiting the scope of this invention.

Example 1

A solution of 25 g. (0.066 mole) of β -diethylaminoethyl 2,2-diphenylpentanoate hydrochloride in a minimum of distilled water is adjusted to pH 8 with dilute sodium hydroxide. The suspension is extracted with ether. The washed ethereal extract is evaporated to leave the oily base which is dissolved in 200 ml. of methanol and reacted with 60 ml. of 30% hydrogen peroxide solution at room temperature for three days.

The oxidation mixture is stirred and cooled while 0.5 g. of platinum oxide is added. After stirring for three hours the filtered reaction mixture is concentrated in vacuo to about one third its volume. The concentrated solution is made up to 250 ml. then saturated with sodium chloride to give an oily layer which is removed and dried. This material is the desired β -diethylaminoethyl 2,2-diphenylpentanoate N-oxide.

Part of this oil is taken up in isopropanol and treated with gaseous hydrogen chloride to give a white product, the hydrochloride derivative, melting at 142-3° C. Drying the sample at 100° C. lowers the melting point to 130-135° C.

Another portion of the base (1 g.) in isopropanol is treated with an excess of ethyl bromide to give the ethyl bromide derivative.

A third portion (500 mg.) in ether is treated on the

steam bath with an excess of methyl iodide to give the methiodide.

Example 2

The N-oxide derivatives of the following compounds are prepared by substituting equimolar quantities of the known tertiary bases (U.S. Patent No. 2,807,566) for the starting material in Example 1.

- β -diethylaminoethyl 2,2-diphenyl-4-methylpentanoate
 β -dimethylaminoethyl 2,2-diphenylpentanoate
 β -piperidinoethyl 2,2-diphenylpentanoate
 β -benzylmethylaminoethyl 2,2-diphenylpentanoate hydrobromide
 β -(cyclopentylethylamino)-ethyl 2,2-diphenylpentanoate hydrochloride
 β -(cyclohexylethylamino)-ethyl 2,2-diphenylpentanoate
 β -dibenzylaminoethyl 2,2-diphenylhexanoate
1-diethylamino-2-ethyl-3-propyl 2,2-diphenyl-6-pentenoate
1-diethylamino-6-hexyl 2,2-diphenyl-4-pentenoate hydrochloride
1-diethylamino-5-pentyl 2,2-diphenyl-4-pentenoate sulfate
 β -diethylaminoethyl 2,2-diphenyl-4-pentenoate benzoate
 β -dimethylaminoethyl 2,2-diphenyl-4-methyl-4-pentenoate
 γ -dibenzylaminopropyl 2,2-diphenyl-4-hexenoate hydrochloride
 β -diethylaminoethyl 2,2-ditolypropionate (U.S. Patent No. 2,423,025)
 β -diethylaminoethyl 2,2-dianisylpropionate (British Patent No. 641,573)
 β -diethylaminoethyl 2,2-di(p-ethylphenyl)propionate (British Patent No. 641,573)
 γ -diethylaminobutyl 2,2-dixylylpropionate (British Patent No. 641,573)

Example 3

A solution of 6.4 g. of γ -diethylaminohexyl 2,2-diphenylpentanoate, prepared from reacting γ -diethylaminohexanol with the acid chloride of 2,2-diphenylpentanoic acid by the Craig method, in methanol is reacted with 15 ml. of hydrogen peroxide solution and worked up as in Example 1 to give γ -diethylaminohexyl 2,2-diphenylpentanoate N-oxide.

This base, in ether, is reacted with sulfuric acid to give the sulfate salt.

Example 4

A solution of 3.5 g. of β -dibutylaminopropyl 2,2-diphenylpentanoate, prepared by reacting β -dibutylaminopropanol in the Craig reaction, in ethanol is reacted with 10 ml. of hydrogen peroxide solution at room temperature overnight and worked up as in Example 1 to give β -dibutylaminopropyl 2,2-diphenylpentanoate N-oxide.

This base, in ether, is reacted with an excess of methyl iodide at reflux to give the methiodide addition compound.

Example 5

A solution of 5.0 g. of β -dimethylaminoethyl 2,2-diphenylpropionate, prepared from the known ingredients 2,2-diphenylpropionic acid chloride and β -dimethylaminopropanol by the Craig method, in methanol is reacted with 15 ml. of hydrogen peroxide solution for two days. Working up as in Example 1 gives the desired β -dimethylaminoethyl 2,2-diphenylpropionate N-oxide and its phosphate salt.

A sample of 500 mg. of the N-oxide in ether is reacted with ethyl bromide on the steam bath to give the ethobromide addition compound.

Example 6

A solution of 2.0 g. of β -diethylaminoethyl 2,2-diphenyl-4-pentenoate (U.S. Patent No. 2,807,566) in aqueous methanolic solution with a 10% hydrogen peroxide concentration is allowed to stand overnight in the dark at room temperature. After working up as in Example 1, the desired β -diethylaminoethyl 2,2-diphenyl-4-pentenoate N-oxide is obtained, M.P. 87-90° C.

What is claimed is:

1. A compound of the formula:

15 in which

R is alkylene having from 2 to 6 carbon atoms;

R_1 is alkyl having from 1 to 8 carbon atoms; and

R_2 and R_3 respectively are members selected from the group consisting of alkyl having from 1 to 8 carbon atoms and benzyl.

2. A compound of the formula:

in which

R is alkylene having from 2 to 6 carbon atoms;

R_1 is alkyl having from 1 to 8 carbon atoms; and

R_2 and R_3 respectively are members selected from the group consisting of alkyl having from 1 to 8 carbon atoms and benzyl;

R_4 is a member selected from the group consisting of hydrogen and alkyl having from 1 to 5 carbon atoms; and

X represents a nontoxic, pharmaceutically acceptable anion.

3. A compound of the formula:

in which

R is alkylene having from 2 to 4 carbon atoms;

R_1 is an alkyl having from 3 to 4 carbon atoms;

R_2 and R_3 respectively are alkyl having from 1 to 4 carbon atoms; and

X $^\ominus$ is a nontoxic, pharmaceutically acceptable anion.

4. β -diethylaminoethyl 2,2-diphenylpentanoate N-oxide hydrochloride.

5. β -diethylaminoethyl 2,2-diphenylpentanoate N-oxide.

6. β -diethylaminoethyl 2,2-diphenylpentanoate N-oxide methiodide.

7. β -diethylaminoethyl 2,2-diphenyl-4-pentenoate N-oxide.
